UNITED STATES PATENT OFFICE.

HENRY F. WOODMANCY, OF WHITINSVILLE, MASSACHUSETTS.

BOLSTER FOR SPINNING-MACHINE SPINDLES.

SPECIFICATION forming part of Letters Patent No. 338,238, dated March 16, 1886.

Application filed July 7, 1884. Serial No. 137,013. (No model.)

To all whom it may concern:

Be it known that I, HENRY F. WOODMANCY, of Whitinsville, in the county of Worcester and State of Massachusetts, have invented a new and useful Improvement in Bolsters for Spinning-Machine Spindles; and I hereby declare that the following is a full, clear, and exact description of the same, reference being had to the accompanying drawings, forming a part of this specification.

The object of the invention is to form a support for a spinning-machine spindle in which the bolster and step are supported, so that when running the spindle may adjust itself to the varying yarn-load.

Another object of the invention is to secure more perfect lubrication of the spindle.

The invention consists in the peculiar and novel construction of the bolster and bolster-case, as will be more fully set forth herein-after.

Figure 1 is a sectional view of the bolster-case, the bolster, and sleeve-whirl, showing the spindle in elevation. Fig. 2 is a sectional view of the combined bolster and step, and Fig. 3 is a sectional view of the bolster-case.

In the drawings, A is the bolster-case provided with the flange a, which rests on the bolster-rail of the spinning-machine, and the screw-thread a', on which a nut is placed to secure the bolster-case to the rail. The tube a² extends above the flange a and above the oil-cup a³.

b is an elastic and sound-deadening ring, forming a support, made, preferably, of cork; but any other material having the capacity to yield and which does not transmit sound may be used in place of cork.

The bolster B, provided with the step at its lower end, is of less diameter than the interior of the bolster-case, so that the lubricant can freely flow around the bolster, and the oil or other lubricant, raised by the revolution of the spindle to the cup b² at the upper end of the bolster, flows down through the holes c c between the tube a² and the bolster, entering the bolster again by the holes c' c' in the bolster-case and step, thus insuring a free circulation of the oil and thorough lubrication of the spindle. Any oil passing between the tube a² and the sleeve b³ and carried to the oil-cup

a³ is carried back into the bolster-case by the hole a'. (Shown in Fig. 3.)

The bolster-case may be made of much larger internal diameter than the outer diameter of the bolster, either in part, as is shown in the drawings, or the whole length, so that a large quantity of oil may be held in the same and thereby the spindle be lubricated for a long time.

The sleeve b³ and the flange b⁴, which forms the cap for the oil-cup, form part of the bolster B, and support the combined bolster and step, with the spindle resting on the elastic ring b and fitting loosely on the outside of the tube a². The sleeve b³ bears against the tube a² holds the bolster-tube concentric in the bolster-case and resists the side pull of the band on the whirl d.

The bolster B is connected with the sleeve b³ at the upper end by a small quantity of metal, that the lower step end of the bolster B may yield slightly in the effort of the spindle and bobbin to adjust themselves, such yielding being restrained by the spring of the metal, so that when the disturbing force ceases the bolster B will return to its true axial position. This automatic adjustment of the spindle, bolster, and step is facilitated by the elastic ring b, on which the bolster and spindle are supported, and, as this ring-support is placed a considerable distance from the axial center of the spindle, the elastic ring b, while it allows the bolster and spindle to adjust themselves to the center of gravity of the yarn-load, offers a springy resistance to such force and returns the bolster and spindle to its true axial position when the disturbing force changes or ceases. The whirl d is formed on the end of the sleeve d', which is secured to the spindle E and rotates with the same. By this improved construction the bolster is suspended within the bolster-case from a point above the center of the whirl, so the spindle may readily find its true center, while the spindle runs without the jar and noise incident to other spindles. The bolster-step and spindle can adjust themselves under sufficient restraint to the yarn-load, and thus prevent all tendency to gyration caused by an unequal yarn-load,

and, as the bolster is suspended in the bolster-case and surrounded by an oil-space, the

lubrication of the spindle is more perfect and the circulation of the oil more uniform.

Having thus described my invention, I claim as new and desire to secure by Letters

5 Patent—

1. The combination, with the bolster-case A, provided with the upwardly-extending tube a^2 , of the bolster provided with the sleeve b^3 , and flange b^4 , constructed to support the bolster and step within the bolster-case, as described.

2. The combination, with the bolster-case A, of the combined bolster and step B, provided at its upper end with the sleeve b^3 and the flange b^4 , constructed to form a cover for the oil-cup and support the bolster and step within the bolster-case, as described.

15 3. The combination, with the bolster-case A, provided with the upward-extending tube a^2 and the oil-cup a^3 , of the combined bolster

and step B, provided with the sleeve b^3 and flange b^4 , and the elastic ring b , constructed to form a yielding sound-deadening support for the spindle, as described.

4. The combination, with the combined bolster and step B, provided with the sleeve b^3 and flange b^4 , and the bolster-case A, provided with the oil-cup a^3 and tube a^2 , of the spindle E, provided with the sleeve-whirl d, the whole constructed to suspend the bolster within the 25 30 bolster-case from a point above the center of the whirl and allow the spindle to find its true center, as described.

In witness whereof I have hereunto set my hand.

HENRY F. WOODMANY.
